UNITED STATES PATENT OFFICE.

DANIEL F. SULLIVAN, OF LOWELL, MASSACHUSETTS, ASSIGNOR TO LAWRENCE MANUFACTURING COMPANY, OF LOWELL, MASSACHUSETTS, A CORPORATION OF MASSACHUSETTS.

KNITTING-MACHINE.

SPECIFICATION forming part of Letters Patent No. 770,942, dated September 27, 1904.

Application filed February 29, 1904. Serial No. 195,749. (No model.)

To all whom it may concern:

Be it known that I, DANIEL F. SULLIVAN, a citizen of the United States, residing at Lowell, in the county of Middlesex and State of Massachusetts, have invented certain new and useful Improvements in Knitting-Machines; and I do hereby declare the following to be a full, clear, and exact description of the invention, such as will enable others skilled in the art to

10 which it appertains to make and use the same.

The present invention relates to an improvement in knitting-machines, and more particularly to striping attachments for circular barbed or spring needle knitting-machines.

15 The object of the present invention is to reorganize and improve the striping attachment for knitting-machines, illustrated and described in my Patent No. 703,973, patented July 1, 1902.

20 In the accompanying drawings, illustrating the preferred form of the invention, Figure 1 is a side elevation of the attachment. Fig. 2 is a front elevation of the thread holding and cutting devices. Fig. 3 is a section on line 25 3 3, Fig. 2. Fig. 4 is a section on line 4 4, Fig. 2, and Fig. 5 is a plan of the operating-cam.

The needle-cylinder 1 is mounted in the usual manner on the bed-plate of the knitting-machine and carries the usual barbed or spring needles 2. The yarn is guided to the needles by yarn-tubes 3 and 4, of which the yarn-tube 3 is shown in the position which it occupies when delivering thread to the looper-wheel to be knit into the fabric. The yarn-tube 3 is carried by a tube-carrying lever 5, pivoted at 6 upon the intermediate lever 7. The yarn-tube 4 is carried in similar manner by the lever 8, pivotally supported at 9 upon the intermediate lever 10. The two levers 7 and 10 are pivotally mounted upon the stud 11, secured to a portion of the frame 12 of the attachment, which in turn is mounted upon the bed-plate of the machine. The rearwardly-extended arms 13 of the intermediate levers 7 and 10 are provided with adjusting-screws 14, the lower ends of which are adapted to bear

upon the forward ends of the cam-levers 15, pivotally mounted at 16 on the frame 12 of the attachment. The rearwardly-extended arms 50 of the cam-levers 15 are provided with portions adapted to be engaged by pins upon pattern-wheels 17, actuated through the medium of the pawl 18, carried by the reciprocating slide-bar 19, which is mounted in suitable 55 bearings in the frame of the device and which carries upon its forward end a cam-roll 20, engaging the cam 21, secured to the needle-cylinder 1.

The tube-carrying levers 5 and 8 are provided with rearwardly-extended arms 22 and 23, respectively, which are provided with curved slots 24 and 25, engaging a fixed pin 27, by virtue of which the ends of the yarn-tubes in passing from their operative to their inoperative positions follow a path of motion 60 which is indicated in dotted lines in Fig. 1, extending from the operative position, in which the end of the yarn-tube 3 is shown, to the inoperative position, in which the end of 65 the yarn-tube 4 is shown. It will be observed that the forward end of this path of motion is curved sharply, so that the end of the yarn-tube 4 in its inoperative position is located 70 within the circle of the needles, but only 75 slightly thereabove. The curving of the slots 24 and 25 secures this path of motion for the ends of the yarn-tubes, and it is considered that this feature of the present construction conduces to the certainty and reliability of the 80 operation of the attachment.

The thread cutting and holding devices are in their general construction and mode of operation similar to the corresponding devices of the said patent. Certain improvements, 85 however, have been embodied in the construction, which are described as follows: The stationary blade 29 of the thread-cutting device is projected downward within and close to the circle of the needles and upon its upper end 90 is provided with a laterally-projected arm 30, which affords a support for the independent downwardly-projected guide-plate 31, which is secured to said arm by means of screws 32.

The plate 31 is slotted at 33 to receive the screws 32, so as to permit the vertical adjustment of the said plate 31 to present it in proper relative position to the thread-guide 40 on the outside of the needles and its removal for convenience in sharpening the stationary knife-blade 29. The guide-plate 31 is provided upon its forward edge with an apron or flange 34, which is extended inwardly down along the forward edge of the guide-plate 31 and along the adjacent portion of the bottom edge of the said guide-plate 31. The margin of this apron or flange constitutes, in effect, a supplementary yarn-guide located behind the guide-plate 31 and in operation independent therefrom, though secured thereto for convenience in construction. The supplementary yarn-guide contributes to the certainty of operation of the machine, particularly when the yarn-tube is thrown into operation. The yarn extending from the holder to the delivery end of the yarn-tube is bent over the edge of the flange 34 when the yarn-tube is thrown into operation, and the yarn extends in a straight line from a point within to a point without the circle of the needles, thereby insuring the correct presentation of the yarn to the needles when it is thrown into operation. This feature of the invention has been adopted owing to the difficulty which has sometimes been experienced with the construction of the said patent, arising from the fact that the yarn when thrown into operation was bent sharply along the tops of the needles, with the result that it sometimes caught there and ran in over the yarn-guide and failed to be knitted into the fabric. This feature of the invention also contributes in a minor degree to the certainty of operation of the device when the yarn is thrown out of operation, as it tends to prevent the yarn from running between the movable blade 35 and inside guide-plate 31 and consequent failure of being cut. The movable knife-blade 35 and the holder 36 are constructed and operated substantially as in the construction of the said patent, except that the shank of the holder 36 is provided with a cam-surface 37, which is engaged by the back edge of the knife-blade when it is retracted to open the holder. The means for operating the movable knife-blade 35 are somewhat different from the construction of the said patent, consisting of the cam-lever 38, which is employed to open the knife-blade, and a spring 39, which is employed to close the same.

The yarn-guide 40, adjustably mounted upon the frame 12 of the machine has its forward end adapted to engage the barbs of the needles and carries a guide-wire 41, which, together with the guide proper, 40, guides the yarn to the looper-wheel 42.

The cam 21, above referred to, which operates the various parts of the device through the medium of the pattern-wheel 17, is constructed with three rises, so that sufficient

time is provided for the successive movements of the parts and their proper co-operation with the thread. The first rise 43 operates to move the slide-bar 19 rearwardly, so as to turn the pattern-wheel 17 sufficiently to 70 operate one of the levers 15 to cause the inoperative yarn-guide to be thrown from inoperative to operative position. The dwell succeeding this rise 43 affords time for the yarn just previously thrown into operation 75 to be knit into the fabric along with the other yarn, so as to make the lap. Then the second rise 44 operates to rotate the pattern-wheel 17, so as to cause the other cam-lever 15 to be moved, so as to throw the other yarn-tube into inoperative position and simultaneously to move the movable knife-blade to open position, thereby separating the knife-blades to receive the yarn just thrown out of operation. The dwell succeeding the rise 44 80 affords time for the passage of the yarn thrown out of operation under the guide-plate 31 and into the opening between the two knife-blades. Then the third rise 45 operates to turn the pattern-wheel 17 still farther, so 85 as to release the cam-lever 38 to permit its spring 39 to cause the movable blade to cut off the yarn thrown out of operation.

The adjustable part 28, carrying the pin 27, is provided with a slot in its shank, so that 90 the pin 27 may be moved vertically and horizontally to vary the path of motion of the yarn-tubes to suit the exigencies of any given case, to cause them to move in the proper path from their operative to their inoperative and from their inoperative to their operative positions, thereby affording a means for independently changing the path of motion and the operative and inoperative position of the delivery ends of the yarn-guides.

The adjusting-screws 14 serve as means for adjusting the positions of the levers 7 and 10, thereby co-operating with the pin 27 in changing the path of motion of the yarn-tubes.

Having thus described the invention, what is claimed is—

1. A circular spring-needle knitting-machine, having, in combination, a needle-cylinder, knitting-wheels, a plurality of movable yarn-guides, and means for moving them including a yarn-guide-carrying lever provided with a curved slot, and a stationary pin for engaging said slot, substantially as described.

2. A circular spring-needle knitting-machine, having, in combination, a needle-cylinder, knitting-wheels, needles carried thereby, a guide-plate located within and close to the circle of the needles, a supplementary yarn-guide located inside of the guide-plate, and yarn-changing devices, substantially as described.

3. A circular spring-needle knitting-machine, having, in combination, a needle-cylinder, knitting-wheels, a guide-plate located within and close to the needles provided with

a flange extending inward from the guide-plate and forming a supplementary yarn-guide, and yarn-changing devices, substantially as described.

- 5 4. A circular spring-needle knitting-machine, having, in combination, a needle-cylinder, knitting-wheels, a yarn-cutter located within and close to the circle of the needles comprising a fixed blade and a movable blade
10 and an inside guide supported within and close to the yarn-cutter and vertically adjustable with relation thereto and independently thereof, substantially as described.
5. A circular spring-needle knitting-machine, having, in combination, a needle-cylinder, knitting-wheels, yarn-changing devices,

a yarn-cutter, a yarn-holder, and means for successively operating the parts to move an inoperative yarn-guide from inoperative position into operative position, then simultaneously to open the yarn-cutter and to throw the other operative yarn-guide from operative to inoperative position and thereafter to cause the cutter to make its cutting stroke, substantially as described. 20

In testimony whereof I affix my signature in presence of two witnesses.

DANIEL F. SULLIVAN.
